APPARATUS FOR KILLING ANIMALS BY
ELECTRICITYKarl Albert Weber, Nedre Bjornstad, Royken,
NorwayApplication April 20, 1932, Serial No. 606,341
In Norway February 1, 1930

4 Claims. (Cl. 175—311)

When killing animals by electricity it is previously known to place the animal in a circuit in such manner that said circuit is closed either through the front legs, body and rear legs of the animal, or through the front legs and the head, and the transmission of the current is obtained by placing the animal on conducting elements or applying conducting electrodes against the body of the animal.

By such transmission of current, however, hair and hoofs have an insulating action and the intermediate resistance becomes great; hair and hoofs will at the places where the current is passing into and out of the animal's body act as two series-coupled condensers of small capacity, and parallel thereto is an ohmic resistance represented by the electric resistance of the sweat pores. A third resistance is that of the interior body, but this resistance is very small relatively to the resistances first mentioned.

The capacitive resistance of the said condensers is very great for low frequencies, but decreases rapidly for increasing frequencies, and is at a frequency of 100,000 cycles per second practically zero, so that only the ohmic resistance remains.

However, for economical reasons high frequency current cannot be used and the present invention therefore relates to a method by which killing current is sent through the animal by means of 220 volts or less, and the essential feature consists therein that the transmission of current from the terminals to preferably the legs of the animal is effected by means of an electrolyte. Hereby the intermediate resistance becomes smaller, as the hair and the hoofs do not act so effectively insulating, and a large surface of contact is obtained so that the current density may be small, and local heat development is entirely avoided.

The annexed drawing illustrates by way of example various apparatus for using the new method.

Fig. 1 shows diagrammatically and partly in section one embodiment of the apparatus and in Fig. 2 is the animal shown placed therein.

Figs. 3 and 4 illustrate two modified embodiments and

Fig. 5 illustrates a detail.

In a narrow passage bound by two fences or low walls 1 is arranged a container 2 of electrically insulating material. By a cross wall 3 of electrically insulating material the container 2 is divided into two compartments 4 and 5, each of which may be lined with an electrically conduct-

ing material if desired. Each compartment is filled with an electrolyte and is by means of a conductor 7 connected to a movable contact 8, which contacts by means of a common operating handle or a lever 9 may be pressed against two fixed contacts 10, which by means of conductors 11 are connected to the current mains 12 through an adjustable transformer. The lever 9 is acted upon by a spring 9' which upon release of the lever always moves the same to such a position that the contacts 8 and 10 do not touch each other.

The animal is led into the container 2 and so placed that the front legs are at one side and the rear legs at the other side of the cross wall 3, and when the contacts 8, 10 are closed the animal closes the circuit. By means of the electrolyte, a contact surface is obtained which is so large that the current density need not be over 0.005 ampere per cm^2 , and at the same time the killing voltage is far below 220 volts. The transformation ratio of the transformer 13 therefore is adjustable from 220/220 to 220/40 volts.

The electrolyte may suitable be a diluted solution of about 2% sodium chloride, but also common water may be sufficient.

In order that it shall be more easy to lead the animal into the container 2 the cross wall 3 may be tiltable as shown in Fig. 5, it being connected to a shaft 14 and through an arm 15 with a loaded handle 16, by means of which the wall 3 may be tilted to and kept in vertical position.

As shown in Fig. 3 the animal may be placed upon grid-like platforms 17, below which are situated a container 2' which is divided in two compartments and filled with electrolyte. By raising the container to the position indicated in dotted lines, the animal is placed in the electrolyte and the circuit may be closed. Instead of using one container 2' having a cross wall, two separate containers may be used and instead of making the container so as to be able to be raised or lowered, the platforms 17 may be so arranged.

In Fig. 4 is shown a third embodiment. By means of pumps 18 is electrolyte pumped through suitable nozzles 19 and delivered as jets to the legs of the animal. The electrolyte is of course connected to the current source as described above.

By means of the new method a surely killing current can be sent through the animal at low voltage, and the arrangement is such that the animal, when it falls, does not open the electric circuit, but keeps the same closed for a sufficient time.

period of time so that the cells in the animal's body lose their power of regeneration.

As will be understood the apparatus here shown and described may be altered in different ways within the scope of the invention.

Having now particularly described and ascertained the nature of my said invention and in what manner the same is to be performed I declare that what I claim is:

- 10 1. In an apparatus for killing animals by electricity, compartments adapted to receive the front and rear legs, respectively, of the animal, a quantity of electrolyte in each of said compartments, said quantities of electrolyte being separate from one another, and means for impressing an electromotive force of killing strength between said separate quantities of electrolyte.
- 15 2. In an apparatus for killing animals by electricity, a single container, the outer surface of which is composed of an electric insulating material and a cross wall of insulating material, dividing said container into two compartments, a quantity of electrolyte in each of said compartments, said quantities of electrolyte being
- 20 25

separate from one another, said compartments being adapted to receive the front and rear legs, respectively, of said animal, and means for impressing an electromotive force of killing strength between said quantities of electrolyte.

3. In an apparatus for killing animals by electricity, a single container, the outer surface of which is composed of an electric insulating material and a tiltable cross wall of insulating material, said wall when tilted dividing said container into two compartments, a quantity of electrolyte in each of said compartments, said quantities of electrolyte being separate from one another, said compartments being adapted to receive the front and rear legs, respectively, of said animal, and means for impressing an electromotive force of killing strength between said quantities of electrolyte.

4. An apparatus according to claim 1 having a support for the animal separate from said containers, and means for moving said support and said containers relatively to each other to effect immersion of the legs of the animal in said electrolyte.
